UNITED STATES PATENT OFFICE.

BERNHARD H. KRUEGER, OF NEW ROCHELLE, NEW YORK.

VANITY-PUFF.

1,326,745.

Specification of Letters Patent. Patented Dec. 30, 1919.

Application filed July 24, 1919. Serial No. 312,986.

To all whom it may concern:

Be it known that I, BERNHARD H. KRUEGER, a citizen of the United States, and a resident of New Rochelle, in the county of Westchester and State of New York, have invented a new and Improved Vanity-Puff, of which the following is a full, clear, and exact description.

The present invention relates to new and useful improvements in toilet articles, and it pertains more particularly to such devices commonly known as powder puffs.

Powder puffs of the ordinary type are manipulated by means of a loop of flexible material, such as ribbon or the like, and in the ordinary construction said manipulating loop is secured in such a manner that it lies flat against the powder puff making it hard to grip when it is desired to use the puff.

It is the primary object of the present invention to secure the manipulating loop to the puff body in such a manner that when the same is not interfered with, it will occupy a vertical position in which it may be readily grasped by the fingers of the operator.

With the above and other objects in view, reference is had to the accompanying drawings in which—

Figure 1 is a perspective view of a powder puff constructed in accordance with the present invention;

Fig. 2 is a transverse sectional view showing the parts in their disassembled relation;

Fig. 3 is a similar view showing the parts in their assembled relation;

Fig. 4 is an elevation partly in section of a modified form of the invention;

Fig. 5 is a fragmentary sectional view of a further modified form of the invention.

Referring more particularly to the drawings, the device comprises two cupped metallic members 5 and 6, the member 6 being smaller in diameter than the member 5 and adapted to be received therein when assembling the several parts of the powder puff. The member 5 is provided with a similar opening 8 of smaller dimensions than the opening 7.

The body of the puff is formed from a suitable pile fabric 9, which latter is cut and stretched about the member 5, with its marginal edge lying on the interior of said member 5, as designated at 10 in Fig. 3. The

reference character 11 designates a suitable finishing material, such as cloth, which is adapted to cover the exposed face of the member 6, and said finishing material has its marginal edge adapted to lie within the member 6, as designated by the reference character 12 in Fig. 3.

In the present form, the manipulating loop consists of a length of ribbon or the like 13, which is bent backwardly upon itself as at 14, to form the loop. The free ends 15 of the loop are secured to the inner face of the member 6 by means of an eyelet or similar tubular member 16, the opposite ends of which are upset as designated by the reference character 17, to secure said eyelet in place. Interposed between the free ends 15 of the loop and the inner face of the member 6, is a disk 18 of any suitable pliable material, and interposed between the outer end of the eyelet 16 and the finishing material 11, is a washer 19 of bone, ivory, or the like, which serves to add to the appearance of the rear face of the puff. By this construction it will be seen that the eyelet 16 serves to secure the finishing material 11, the cup-shaped member 6, the manipulating loop 13, and the ornamental washer 19, together, and forms the only fastening means for these several parts.

After the several parts have been assembled as described and shown in Fig. 2, the loop is forced through the eyelet 16, as shown in Fig. 3, and projects from the rear side of the puff to form suitable means by which the puff may be manipulated by the operator.

In the modified form of the invention shown in Fig. 4, the manipulating loop is secured in the same manner as in the form above described, except that in the modified form of the invention in order that its cost of manufacture may be cheapened, the ordinary washer 19 is eliminated and the eyelet or tubular sleeve 16 is reduced in length.

In the form of the invention shown in Fig. 5, the washer 18 has been eliminated, the eyelet 16 passing through the opening 8 in the cup-shaped member 6, said opening being of a size equal to the exterior diameter of said eyelet 16.

From the foregoing description, it will be apparent that the present invention provides for the construction of a powder puff

in which the manipulating loop thereof will at all times occupy a position in which it may be readily grasped, and, at the same time, the invention provides an effective 5 means for securing the manipulating loop to the puff.

Having thus described the invention, what is claimed as new is:

1. A powder puff comprising a front and 10 a rear member, said rear member being provided with a centrally arranged opening, a tubular member passing through said opening, and a manipulating loop secured to the inner face of said rear member by said tubular member, said loop being subsequently 15 passed through said tubular member to the exterior of the rear face of said puff.

2. In a powder puff, a rear member having a substantially central opening, a flexible 20 manipulating loop secured on the interior of said rear member, and means in said central opening for securing said manipulating loop in operative position, and said manipulating loop being subsequently

passed through the central opening to the 25 exterior of the rear member.

3. In a powder puff, a rear member having a central opening, a suitable finishing material covering the outer face of said rear member, a manipulating loop passed 30 through said central opening in the rear member, and an eyelet passed through said central opening in the rear member and serving to secure the finishing material and loop to the rear member adjacent said central opening.

4. In a powder puff, a rear member provided with a centrally disposed opening, a finishing material for covering the outer face of said rear member, an eyelet adapted 40 to be passed through said central opening and have its ends upset to secure the finishing material to the rear member and a manipulating loop projecting from the interior of the puff through said eyelet to the 45 exterior of the puff.

BERNHARD H. KRUEGER.
